UNITED STATES PATENT OFFICE.

KARL H. HANSEN, OF SEWICKLEY, PENNSYLVANIA.

BUFFER FOR CARS.

1,236,558.

Specification of Letters Patent. Patented Aug. 14, 1917.

Application filed May 15, 1916. Serial No. 97,613.

To all whom it may concern:

Be it known that I, KARL H. HANSEN, a subject of the Emperor of Germany, and resident of Sewickley, in the county of Allegheny and State of Pennsylvania, have invented a new and useful Improvement in Buffers for Cars; and I do hereby declare the following to be a full, clear, and exact description thereof.

10 My invention relates to buffers for cars, and more particularly to cars of the lighter type for use in industrial work, mines, and in the grading for railroad construction, etc.

The object of my invention is to provide 15 a spring buffer which is simple in construction and which will relieve the car not only against a pushing strain, but also a pulling strain, so that the wear and tear on the underframe is greatly reduced, while at the 20 same time greater ease in the starting of the car is obtained.

In the accompanying drawing, Figure 1 is a plan view of the car underframe, showing my invention applied thereto; Fig. 2 is 25 an enlarged section on the line 2—2, Fig. 1; and Fig. 3 is a section on the line 3—3, Fig. 2.

In the drawing, the numeral 2 designates a suitable car underframe of the round 30 buffer type in the sense that the end portions 3 are rounded, which gives greater ease of operation on curves. This underframe may be made up of channel members of suitable strength, said frame having the cross-members 4 at or near the ends and the middle cross-member 5. The cross-members 4 are connected to the frame 2 by the angles 6.

The buffer caps 7 are preferably formed 40 of plate metal bent into U-shape, the upper and lower plates 8 and 9, respectively, of said cap inclosing the end portion 3 of the frame 2 and extending back the proper distance, the top plate 8 of said cap resting on the upper flanges of the channel member 45 forming the front portion 3 and the channel member 4.

The guides 10 are secured to the front portion 3, and the cross member 4 to the frame guides for the cap member 7, and to prevent 50 lateral movement of same, said guides further acting to strengthen the underframe. The reinforcing channel member 11 is inserted in the front portion 3 between the guides 10 to reinforce and strengthen the 55 frame.

A spacer 12 is inserted between the upper and lower plates 8 and 9 of the cap member, said spacer having an opening 13 formed through it for the passage of the coupling pin 14, said coupling pin being secured in place by the nut 15. The coupling pin passes through openings formed in the upper and lower plates 8 and 9 of the cap member, and the cap member is held in place by the coupling pin so that by the removal of the coupling pin the cap plate may be removed for 60 repairs or for the substitution of a new one.

A spring 16 is interposed between the spacer 12 and the cross-member 4, and a rod 17 journaled in said spacer and having the 70 head 17* adapted to seat against a shoulder in the spacer and is connected by the turnbuckle 20 to the rod 21 which in turn is connected to a spacer of like construction at the opposite end of the frame, where the parts 75 already recited are duplicated, so that the buffers at each end of the underframe are connected by a continuous draw bar made up of the rods 17 and 21 connected by the turnbuckle 20.

It may be desirable to form the spacer 12 and rod 17 as a single unit, such as a forging, and I do not desire to limit my invention to the construction shown and described.

The coupling pin 14 has the T-head 22 85 which is engaged by the links of the coupling chain 23. In coupling, the link is slipped over the head and turned practically at right angles so that the link is held beneath the T-head securely in position, and 90 the coupling operation is done without the operator having to extend his hands down between the bumpers. It is apparent that other forms of coupling-pin head may be employed without departing from the principle of coupling; for instance, instead of the T-headed pin, a simple hook may be employed, or the pin having a hole for the bolt of a clevis hitching. It is true that the pulling strength is eccentric to the center line of 100 the draw bar, but on account of the width of the buffer and length this force is transferred to the draw bars without causing the couplers to twist or bind in any way and the full strength and service of the buffers is obtained without their having to be cut out.

It will be observed that when one car 105 bumps into the other, the buffers yield under the action of the spring to relieve the shock, while on the other hand, when a pulling 110

force is applied to the buffer the springs also relieve the strain and greater ease in starting the car is obtained.

Furthermore, by my improved form of buffer, the buffer projects very little beyond the end of the underframe, so that no difficulty is experienced in curves due to interlocking of the coupling heads and which was liable to cause the cars to leave the track. Again, the fact that the coupling-pin passes through the buffer inside the frame obviates the liability of the hand of the operator getting between the bumpers in the coupling operation.

15 15 What I claim is:

1. The combination with the car under-frame, of a spring-actuated buffer engaging said frame, and a car coupling pin passing through said buffer inside said frame.

20 2. The combination with the car under-frame, of a spring-actuated buffer comprising a U-shaped cap member, a spacer in said cap member, and a coupling pin passing through said cap member and said

25 spacer.

3. The combination with the car under-frame having cross members intermediate the ends, cap members engaging the end portions of said frame, spacers in said cap members, springs interposed between said spacers

and said cross members, a rod connecting said spacers and coupling pins passing down through cap members and spacer.

4. The combination with a car underframe having cross-members intermediate the ends, 35 cap members engaging the ends of the underframe, spacers in said cap members, and sleeve extensions on said spacers, springs encircling said sleeve extension and interposed between said spacers and said cross-members, a rod engaging said sleeve extension, 40 and a coupling pin passing through said cap members and through said spacers.

5. The combination with a car under-frame having cross-members intermediate 45 the ends, cap members engaging the ends of the underframe, spacers in said cap members, and sleeve extensions on said spacers, springs encircling said sleeve extension and interposed between said spacers and said 50 cross-members, a turnbuckle rod engaging said sleeve extensions, and a coupling pin passing through said cap members and through said spacers.

In testimony whereof, I the said KARL H. 55 HANSEN, have hereunto set my hand.

KARL H. HANSEN.
